UNITED STATES PATENT OFFICE

2,081,974

CABLE SUSPENSION

Edwin E. Arnold, Pittsburgh, Pa., assignor to
Westinghouse Electric & Manufacturing Com-
pany, East Pittsburgh, Pa., a corporation of
Pennsylvania

Application January 11, 1935, Serial No. 1,292

8 Claims. (Cl. 173—251)

The present invention relates to suspension devices for electrical transmission lines and more particularly to a device which permits cable vibrations to pass freely through it, thereby minimizing the possibility of breakage of the cable due to molecular fatigue.

In suspension devices of the prior art, it has been usual practice to grip or clamp the conducting cable at or in the supporting shoe which, in turn, is secured to the bottom of a string of insulating units. With such construction, however, vibrations in the cable in a vertical plane cause a bending of the cable at the point of clamping which eventually results in molecular fatigue of the cable strands and consequent breakage thereof.

In Patent No. 2,005,881 issued June 25, 1935 to E. E. Arnold and C. L. Fortescue, and assigned to the Westinghouse Electric & Manufacturing Company, a construction is shown which has proved to be quite successful in practice but life tests have indicated a number of desirable changes to increase its efficiency. Accordingly, the object of the present invention is to improve the construction shown in said patent.

According to the present invention, a resilient strip is disposed beneath the cable longitudinally thereof and is supported adjacent its midpoint by a shoe which, in turn, is pivotally supported from the bottom of a string of insulators. The ends of the strip are clamped to the cable in a particular manner and pads or liners of a material softer than that of the cable are interposed between the cable and the resilient strip and between the cable and the end clamps. In addition, means are provided to insure that various elements of the assembly are maintained in proper operating relation under normal service conditions and there are a number of structural features to improve the assembly over that shown in the aforesaid Patent No. 2,005,881, as pointed out hereinafter.

Referring to the drawing,

Figure 1 is a view in elevation, partly in section, of the cable supporting assembly constituting the present invention.

Figs. 2 and 3 are views in plan and vertical section, respectively, of a clamping shoe constituting part of the present invention.

Figs. 4 and 5 are views in plan and vertical section, respectively, of a clamping shoe for cooperation with the shoe shown in Figs. 2 and 3.

Fig. 6 is a view in perspective of a clamping device for the shoes shown in Figs. 2 through 5.

Fig. 7 is an enlarged plan view of a resilient cushioning member shown in Fig. 1.

Fig. 8 is a view in section on the line VIII—VIII of Fig. 7.

Fig. 9 is a view in vertical section of the device shown in Fig. 7.

Fig. 10 is a fragmentary view of a portion of Fig. 1.

Fig. 11 is a plan view of a clamping strap shown in Fig. 1, and

Fig. 12 is a view on a reduced scale of a vertical section taken on the line XII—XII of Fig. 1.

Referring more specifically to the drawing and particularly Fig. 1 thereof, the invention contemplates a supporting clamp for a stranded cable 1 including an elongated strip 2 of resilient material, such as spring steel, which extends below the cable 1 longitudinally thereof.

A supporting shoe 4 embraces the strip 2 substantially at the midpoint of the latter, and includes a central depressed portion for receiving a similarly curved portion of the strip 2. It is to be understood that the strip 2 extends equal distances on each side of the lateral center line of the shoe 4, a portion of the cable 1 and strip 2 to the right of such center line being broken away in Fig. 1.

A liner 6 of resilient material is disposed between the conductor 1 and the strip 2 to provide a cushioning effect between the conductor and strip. The liner 6 is shown in detail in Figs. 7 through 9. It is provided with a longitudinally extending channel which conforms more or less to the curvature of the cable 1 and has depending ears 7 adapted to straddle the lateral center line of the shoe 4.

The material of which the liner 6 is formed may be any of the so-called synthetic rubber compounds which show substantially no deterioration under varying weather conditions, and I have found that a suitable compound is a stable isoprene derivative of the chlorinated type known commercially as "Duprene".

The surfaces of the depression in the shoe 4, the deformed portion of the strip 2 and the contour of the ears 7 are so related that the strip 2 and liner 6 are substantially nested in the depression in the shoe to prevent relative movement therebetween axially of the conductor 1.

A supporting stirrup 10 having a suitable supporting socket 11 at the upper end thereof is adapted to straddle the shoe 4 and is pivoted thereto by a bolt 12. The point of pivotal sup-

port is substantially coaxial with the arc formed by the depending ears 7 on the strip 6 and the bolt 12 extending through the clamp between such ears affords additional means for maintaining the elements 2, 4 and 6 in operative position. It is to be noted that with the bolt 12 in position, the strip 2 cannot be removed therefrom in either a vertical or horizontal direction.

Clamping shoes 14 and 16, of a relatively light weight material, such as an aluminum alloy, having grooved inner surfaces, substantially conforming to the curvature of the cable 1, are clamped to the cable adjacent to the free ends of the strip 2 by U-bolts 18 of the form shown in Fig. 6. Each free end of the strip 2 is disposed between a U-bolt 18 and a lower clamping shoe 16, and is provided with punched portions, as shown in Fig. 10, providing at each end of the strip a depression in the upper face thereof, 20 and a lug on the lower face thereof.

A suitable aperture or depression 19 is provided in the bottom of the U-bolt 18 to receive the lug on the lower face of the strip 2, and a lug on the under face of the lower shoe 16 25 adapted to be received within the recess formed in the upper face of the strip 2. These interfitting deformed portions on the shoe 16, strip 2, and U-bolt 18 maintain these elements in proper operative relation and prevent relative movement therebetween in a direction longitudinally of the strip 2 under operating conditions.

The threaded ends of the U-bolt 18 project through suitable openings 28 cast into the upper clamping shoe, and the arms of the U-bolt 18 35 extend between projections 21 cast in the lower clamping shoe.

By reason of the clamping construction heretofore described, a single U-bolt 18 is sufficient to exert an efficient clamping force whereby all 40 of the elements are maintained in proper operative position and the strip 2 securely clamped to the conductor.

It has been found in practice that, with clamping shoes of the usual type, there will be some 45 abrasion of the conductor strands between the two shoes 14 and 16. In order to avoid this condition, it is proposed in the present invention to provide a liner on the surfaces of the shoes which contact with the conductor 1. In a preferred form, the liner may be of a metal or alloy somewhat softer than the metal of the cable or it may be of some rubber-like composition which is sufficiently impervious to weather and temperature conditions, such as a material 55 similar to that of the liner 6. Such material is sufficiently hard and dense to withstand the rather severe strains imposed upon it but is sufficiently soft to permit the cable strands to become slightly imbedded in it, to thereby increase the clamping area of the shoes 14 and 16.

Referring to Figs. 3 and 5, a liner 22 substantially covers the inner grooved face of the shoe members and it may be either of a relatively 60 soft and light-weight metal or alloy, or a rubber-like composition, as above described. As shown in Figs. 3 and 5, however, the liner 22 is of a rubber-like composition which is maintained in position partly by adhesion to the wall 65 of the shoe and partly by a soft metal plug 24 which is hammered through the liner into a suitable depression in the shoe member. Inasmuch as the shoe members are of conducting material and the liner 22 is of dielectric material, it is desirable to provide an electrical con-

nection between the cable and the shoe members to bring these elements to the same electrical potential. The plugs 24, therefore, serve the dual purpose of maintaining the liners 22 in position and affording a direct electrical connection between the cable and shoe elements, thereby eliminating the possibility of an electrical discharge between the parts with attendant interference to radio reception.

Tests on a cable suspension, as above described, indicate that as vibrations pass along the cable, there is a tendency for the cable to touch the strip 2 along an area between the clamp 14, 16 and the supporting shoe 4. Under cases of severe vibration, the cable hits the strip 15 with sufficient force to deform the strands of the cable and in order to alleviate this condition an auxiliary clamping device is provided for limiting the vertical movement of the cable with respect to the strip, and for spacing the cable 20 from the strip. This device includes a strap of soft sheet material, such as aluminum, as shown in Fig. 11, having a tongue portion 26 and a body portion having apertures 27 and 28 therein, adapted to be wrapped around the cable, 25 strip 2, and a spacing element 30 between the strip 2 and cable.

The spacing element 30 comprises a block of material softer than that of the cable, and may be of the same material as the liner 6 or 22. 30 The block has a grooved upper surface for receiving the cable 1, and a flat bottom surface with a centrally disposed lug 31.

At the point where the auxiliary clamping device is to be disposed, the strip 2 has a punched 35 or deformed portion of the same general character as shown in Fig. 10, to provide a depression on the upper face of the strip and a lug 29 on the under surface thereof. The depression is adapted to receive the lug 31 of the spacing element 30, and the lug 29 is adapted to project through aperture 28 in the strap shown in Fig. 11, when the strap is wrapped around the cable 40 with its tongue 26 drawn through the opening 27 and return-bent upon itself, to maintain the 45 block 30, cable and strip 2 in operative relation.

When the suspension is installed for service on a transmission line, damaging vibrations occurring on the cable usually occur in a vertical plane and by reason of the fact that the cable is clamped at widely spaced points to the resilient strip 2, such vibrations may pass relatively freely through the suspension device; the portion of the cable extending through the light-weight shoe 4 being free to move vertically between the arms of 50 the saddle 10. Because of the liner 6 of relatively soft material and the block 30 of similar material there will be no pounding of the cable against the hard metal parts of the support thereby insuring longer life of the cable. In addition, because 55 of the peculiar and novel construction of the clamps for the end of the strip 2, there will be no relative slipping between the cable and the strip 2 at these points of clamping.

It should be apparent from the foregoing, that 60 the suspension device above described is a distinct improvement over the prior art, including that represented by Patent No. 2,005,881, above referred to, and it has been found in practice that 65 substantially improved operation results from such construction.

Quite obviously, many modifications may be 70 made in the construction described without departing from the spirit and scope of the invention, and it is desired that no limitations shall be 75

placed thereon except as imposed by the prior art and the appended claims.

I claim as my invention:

1. A suspension device for cables comprising an elongated strip of spring material for disposition beneath the cable longitudinally thereof, means for rigidly clamping the ends of said strip to the cable, a shoe engaging substantially the midpoint of said strip in supporting relation, means for pivotally supporting said shoe, a spacing member of softer material than said cable between said strip and cable within said shoe, and correspondingly shaped portions on said spacing member, strip and shoe interfitted to prevent relative displacement therebetween in a direction parallel to the cable axis.

2. A suspension device for cables comprising an elongated strip of spring material for disposition beneath the cable longitudinally thereof, means for securing the ends of said strip to the cable, a shoe engaging substantially the midpoint of said strip in supporting relation, means for pivotally supporting said shoe, a spacing member of a material softer than said cable between said strip and cable within said shoe, correspondingly shaped portions on said spacing member, strip and shoe interfitted to prevent relative displacement therebetween in a direction parallel to the cable axis, and means comprising a part of said pivotal supporting means extending between the strip and spacing member for preventing displacement of said strip with respect to said shoe in a direction perpendicular to the axis of said cable.

3. A suspension device for cables comprising an elongated strip of resilient material for disposition beneath the cable longitudinally thereof, a shoe engaging substantially the midpoint of said strip in supporting relation, means for pivotally supporting said shoe including means for maintaining said strip in operative position, means for clamping the free ends of said strip to the cable each including a clamping shoe disposed between the strip end and the cable, a clamping device embracing the strip end, shoe and cable, and interfitted portions on said shoe and strip for preventing relative movement therebetween in a direction longitudinally of the strip.

4. A suspension device for a cable comprising an elongated spring strip for disposition beneath the cable substantially parallel thereto, supporting means engaging the midpoint of said strip

and free of the cable, and clamps for securing the free ends of said strip to the cable each comprising a lower shoe and an upper shoe embracing the cable, clamping means surrounding the end of said strip and the lower shoe, and deformed portions on said lower shoe and strip end in interfitting engagement.

5. A suspension device for a cable comprising an elongated strip for disposition beneath the cable substantially parallel thereto, supporting means engaging the midpoint of said strip and free of the cable, and clamps for securing the free ends of said strip to the cable each comprising a lower shoe and an upper shoe embracing the cable, clamping means surrounding the end of said strip and the lower shoe, and deformed portions on said lower shoe and strip end in interfiting engagement, said shoes being lined with a material softer than that of the cable in engagement with the cable.

6. A suspension device for a cable comprising an elongated strip for disposition beneath the cable substantially parallel thereto, supporting means engaging the midpoint of said strip and free of the cable, and clamps for securing the free ends of said strip to the cable each comprising a lower shoe and an upper shoe embracing the cable, clamping means surrounding the end of said strip and the lower shoe, and deformed portions on said lower shoe, strip end, and clamping means in nested relation for preventing relative movement therebetween in a direction parallel to the cable axis.

7. A clamp for an electrically conducting cable comprising upper and lower clamping shoes adapted to embrace the cable, and means for clamping them in such position, said shoes having a lining of dielectric material softer than the material of the cable in engagement with the cable, and means establishing an electrical connection between said shoe and cable through said dielectric lining.

8. In a clamp for an electrical cable including a clamping shoe, a resilient pad of dielectric material for disposition between said shoe and cable, means for securing said pad to the shoe including a metallic member of a material softer than that of the cable constituting an electrical connection between said shoe and cable extending through the dielectric pad.

EDWIN E. ARNOLD.
